UNITED STATES PATENT OFFICE.

WALTER S. STEVENSON, OF PHILADELPHIA, PENNSYLVANIA.

DESIGN FOR A FURNACE-GRADE.

SPECIFICATION forming part of Design No. 24,458, dated July 2, 1895.

Application filed February 21, 1895. Serial No. 539,286. Term of patent 14 years.

To all whom it may concern:

Be it known that I, WALTER S. STEVENSON, a citizen of the United States, residing in Philadelphia, Pennsylvania, have invented a certain Design for a Furnace-Grate, of which the following is a specification.

My design for a stove-grate is fully shown in the accompanying drawings, in which—

Figure 1 is a plan view of the grate. Fig. 2 is a perspective view of the same, and Fig. 3 is a transverse section of one of the bars.

The design comprises two segregable features—namely, the frame and the bars.

The frame comprises the front web *a*, the intermediate transverse web *b*, and the back web *d*, these three webs being connected by side webs, which as to their front portions *f* are straight and at right angles to the front web, and as to their rear portions *f'* are inwardly curved and less in width than the front portions *f*, and have near the back web *d* a sharp inward offset *f''*, the back web *d* being much narrower than the front web *a* of the frame.

Each of the bars *i* of the grate is of polygonal cross-sectional form and has at short intervals throughout its length groups of projecting ribs or fingers *i'*, each group comprising three equidistant fingers, as shown in Fig. 3, and around each of these fingers extends a groove *i''*.

I claim—

1. The design for a stove grate, substantially as described and shown.

2. In a design for a stove grate, the design for the frame, substantially as described and shown.

3. In a design for a stove grate, the design for the bar, substantially as described and shown.

In testimony whereof I have signed my name to this specification in the presence of two subscribing witnesses.

WALTER S. STEVENSON.
